UNITED STATES PATENT OFFICE.

JAMES H. PETERSON, OF NEW YORK, N. Y.

SCRAPING TOOL OR IMPLEMENT.

No. 830,451.

Specification of Letters Patent.

Patented Sept. 4, 1906.

Application filed September 6, 1905. Serial No. 277,139.

To all whom it may concern:

Be it known that I, JAMES H. PETERSON, a citizen of the United States, residing at New York, in the county of New York and State of New York, have invented certain new and useful Improvements in Scraping Tools or Implements; and I do hereby declare the following to be a full, clear, and exact description of the invention, such as will enable others skilled in the art to which it appertains to make and use the same, reference being had to the accompanying drawings, and to numerals of reference marked thereon, which form a part of this specification.

15 This invention has reference generally to improvements in scraping tools or implements; and the invention relates more particularly to a novel scraper which is especially adapted for use in scraping the hard wood of parquet floors, but which may also be used in cabinet-work and other purposes where the scraping of a surface is desired.

20 My invention has for its principal objects to provide a novel and simply-constructed scraper in which the handle is connected with the blade near and as closely to the scraping edge of the blade as is possible, whereby greater pressure can be brought upon the scraping edge of the tool when in use, thus enabling the same to be brought in firmer engagement with the surface which is to be scraped and with a less tiring effect upon the hands of the operator.

25 A further object of this invention is to provide a novel scraping-tool in which the scraping-blade is made very thin, being properly backed to prevent bending, said thin blade being readily tempered and its scraping edge consequently being kept sharp for a very long time and when dull being readily sharpened.

30 A still further object of this invention is to provide a scraper in which the blade is adjustable and can be positively locked in its adjusted positions.

35 Other objects of this invention not at this time more particularly mentioned will be clearly evident from the following detailed description of the invention.

40 With the various objects of my present invention in view the said invention consists, primarily, in the novel scraping tool or implement hereinafter set forth; and, furthermore, this invention consists in the various arrangements and combinations of parts, as well as in the details of the construction of

the same, all of which will be hereinafter more fully described and then finally embodied in the clauses of the claim.

The invention is clearly illustrated in the accompanying drawings, in which—

Figure 1 is a side elevation of the tool embodying the principles of this invention; and Fig. 2 is a longitudinal vertical section of the tool, a portion of the handle being shown in elevation. Fig. 3 is a front end view of the tool looking in the direction of the arrow X in Fig. 1, and Fig. 4 is a transverse section taken on line 4 4 in said Fig. 1 looking in the direction of the arrow Y.

Similar characters of reference are employed in the said views to indicate corresponding parts.

Referring now to the said drawings, the reference character 1 indicates the complete scraping tool or implement, the same comprising a suitable handle 2, with which is connected a yoke or other suitably-shaped blade-supporting frame 3. This frame is secured against the usually ferruled end of the handle, preferably by means of a stem or shank 4, which is driven into the end of the handle, as shown in Fig. 2 of the drawings. The said frame 3 is also provided with a pair of forwardly-extending fingers or arms 5, having holes or perforations near their forward ends for the reception of pins or screws 6 and 7. One of said screws, as 6, is made with a right-handed screw-thread 8, and the other screw 7 is made with a left-handed screw-thread 9. Pivotally arranged in the space between the said fingers or arms 5 is a supporting-plate 10, which is provided, preferably along its lower marginal edge, with a pair of tubular ears or lugs 11, through which the respective pins or screws 6 and 7 extend, with the screw-threaded end portions of said pins or screws 6 and 7 projecting toward each other, substantially as shown in Fig. 3 of the drawings. The respective right and left handed screw-threaded portions of said screws or pins 6 and 7 are respectively arranged in correspondingly-formed screw-threaded receiving-sockets of

50 a nut or collar 12, the said collar in the present case being provided with recesses or depressions 13 for a spanner-wrench or other similar tool, whereby the said nut or collar 12 may be turned to cause the said screw-threaded portions of the said pins or screws 6 and 7 to be drawn closer together or forced farther apart, according to the direction in

which said nut or collar 12 is turned. Thus it will be clearly evident that when the said pins or screws 6 and 7 are drawn toward each other the end portions of the two fingers or arms 5 of the frame 3 are made to bind against the ends of the respective ears or lugs 11 of the supporting-plate 10, whereby the latter can be secured and retained in any one of its adjusted positions, as clearly indicated in Fig. 1 of the drawings. The said supporting-plate 10 is also provided with a pair of rearwardly-projecting perforated ears or lugs 14, in which are arranged and suitably secured the respective end portions of a rod or pin 15. The scraper-blade is indicated by the reference character 16, the said blade being of suitable length and being placed against the inner face of the supporting-plate 10, with the lower and knife or scraping edge 17 of the blade 16 extending below the plane of the lower edges of the two fingers or arms 5. That the said scraper-blade 16 may be positively secured in its vertically-adjusted relation upon the inner face of the supporting-plate 10 a holding-plate 18 is provided, said plate 18 having its lower marginal edge 19 arranged against the blade 16 and having its central portion resting upon the inner edge portion of the rod or pin 15, the binding or tightening relation of the holding-plate 18 being produced by a cone-shaped member or socket 20 and a screw or bolt 21, arranged in a screw-hole 22 in said socket or member 20. That the binding or holding pressure of the end portion of said screw or bolt 21 may be in a direction at right angles upon the face of the scraper-blade 16, as indicated in Figs. 1 and 2 of the drawings, the said cone-shaped member or socket 20 has a swivel-like motion in a correspondingly-formed hole 23 in the holding-plate 18, so as to move freely in said hole when the screw or bolt 21 is turned, thus causing the said socket or member 20 to adapt itself to the most efficient position and prevent any distortive movements of the parts during the act of tightening the scraper-blade 16 in its vertically-adjusted position upon the supporting-plate 10, as will be clearly understood.

From the foregoing description of my present invention it will be seen that I have devised a simply-constructed scraper tool or implement the scraper-blade of which is quickly and easily removed from the frame and handle of the tool for various purposes, and by the proper manipulation of the screw or bolt 21 and parts connected therewith the said scraper-blade is also easily brought into vertically-adjustable relation upon the inner face of the supporting-plate 10. The scraper-blade 16 is also capable of an angular adjustment by the proper manipulation of the nut or collar 12, according to existing conditions in scraping a surface.

Having thus described my invention, what I claim is—

1. In a scraper, the combination of a handle, a yoke-shaped blade-supporting frame comprising forwardly-extending fingers, each finger being provided with a screw-receiving perforation, a screw in each perforation, one of said screws being formed with a right-handed screw-thread, and the other screw being formed with a left-handed screw-thread, a blade-supporting plate, said plate being provided with a pair of pivot lugs or ears, through each one of which one of said screws extends, a right and left screw-threaded nut between said pivot-lugs with which said screws are operatively connected, so that when said nut is turned, said fingers of the supporting-frame and the pivot-lugs will be brought into binding relation, to hold said supporting-plate rigidly in any one of its adjusted positions with relation to the plane of the handle, and means for securing the scraper-blade in its adjusted position against the face of said supporting-plate, substantially as and for the purposes set forth.

2. In a scraper, the combination of a handle, a yoke-shaped blade-supporting frame comprising forwardly-extending fingers, each finger being provided with a screw-receiving perforation, a screw in each perforation, one of said screws being formed with a right-handed screw-thread, and the other screw being formed with a left-handed screw-thread, a blade-supporting plate, said plate being provided with a pair of pivot lugs or ears, through each one of which one of said screws extends, a right and left screw-threaded nut between said pivot-lugs with which said screws are operatively connected, so that when said nut is turned, said fingers of the supporting-frame and the pivot-lugs will be brought into binding relation, to hold said supporting-plate rigidly in any one of its adjusted positions with relation to the plane of the handle, and means for securing the scraper-blade in its adjusted position against the face of said supporting-plate, consisting of a holding-plate and a pair of pivot-lugs extending rearwardly from said supporting-plate, between which said holding-plate is pivotally supported, and a binding screw or bolt on said holding-plate, substantially as and for the purposes set forth.

3. In a scraper, the combination of a handle, a yoke-shaped blade-supporting frame comprising forwardly-extending fingers, each finger being provided with a screw-receiving perforation, a screw in each perforation, a blade-supporting plate, said plate being provided with a pair of pivot lugs or ears, through each one of which one of said screws extends, and a tightening means connected with said screws for bringing the fingers of the supporting-frame and said pivot-lugs of

said blade-supporting plate in binding relation, to hold said supporting-plate rigidly in any one of its adjusted positions with relation to the plane of the handle, and means for securing the scraper-blade in its adjusted position against the face of said supporting-plate, substantially as and for the purposes set forth.

4. In a scraper, the combination of a handle, a yoke-shaped blade-supporting frame comprising forwardly-extending fingers, each finger being provided with a screw-receiving perforation, a screw in each perforation, a blade-supporting plate, said plate being provided with a pair of pivot lugs or ears, through each one of which one of said screws extends, and a tightening means connected with said screws for bringing the fingers of the supporting-frame and said pivot-lugs of said blade-supporting plate in binding relation,

tion, to hold said supporting-plate rigidly in any one of its adjusted positions with relation to the plane of the handle, and means for securing the scraper-blade in its adjusted position against the face of said supporting-plate, consisting of a holding-plate and a pair of pivot-lugs extending rearwardly from said supporting-plate, between which said holding-plate is pivotally supported, and a binding screw or bolt on said holding-plate, substantially as and for the purposes set forth.

In testimony that I claim the invention set forth above I have hereunto set my hand this 6th day of September, 1905.

JAMES H. PETERSON.
